ABSTRACT OF THE DISCLOSURE

A fastener driving tool is provided with front and rear sections of a gun structure, the rear section being pivotably secured in a casing for movement between an operative position in axial alignment with the front section and an inoperative position in which the rear section is accessible for reloading. The front section is threadably engaged with the casing and is turnable for being axially abutted with the rear section in the operative position and released therefrom in the inoperative position. A striker in the rear of the casing is controlled by a cocking slider and trigger to act on a cartridge in the rear section to expel a fastener.

The present invention has for its object a single barreled plugging pistol or apparatus including a longitudinally open body or carcass to which is pivotally secured the rear section of the gun, so as to allow through the agency of a lever its transverse release with reference to said carcass and thereby the removal and reloading of the cartridge carrier out of said rear section.

Said rear pivoting section of the gun is held locked in its axial closed firing position by the front section of said gun which is screwed into the corresponding opening of the carcass and may be angularly shifted through the agency of a projection formed on an outer movable collar.

According to a further feature of the invention, the pistol-cocking slider cooperates through a stud thereon with a shoulder on the movable collar so as to form safety means and to allow the cocking and firing of the pistol only when the rear section of the gun is closed and locked in position.

According to a further object of the invention, the pistol cocking slider includes two parts of which the adjacent interconnected ends engage each other so that the front end of the slider carrying the muzzle of the gun may be held in position by the splinter shield when in its operative position, said front end of the slider being automatically disconnected from the remainder of the apparatus under the mere action of gravity as soon as the shield is dismantled, which ensures safety for the apparatus.

According to a further feature of the invention, the splinter-proof shield is constituted by two arcuate parts extending over angles the sum of which forms 360° so as to allow the shield to cope with the requirements of the work to be executed, by a relative angular shifting between said parts.

According to a still further object of the invention, a rocking safety lever located at the lower end of the carcass holds automatically the cocking slider if the pistol happens to be dropped or subjected to a shock which might otherwise shift the cocking slider and cock the pistol.

These and other further advantageous features will appear clearly from the reading of the following description, reference being made to the accompanying drawings given solely by way of example and by no means in a limiting sense. In said drawings:

FIG. 1 is on a reduced scale an outer front view of

2

the single barreled plugging pistol executed in accordance with the invention, the position illustrated being the normal position for which the rear section of the gun is held inside the carcass while the pistol is inoperative since, far from being set, it is locked against operation.

5 FIG. 2 is a view of the pistol as seen from outside in a direction at 90° with reference to that in which it is seen in FIG. 1.

FIG. 3 is a general longitudinal sectional view of the 10 plugging pistol illustrated in FIG. 1.

FIG. 4 is a longitudinal sectional view through line IV—IV of FIG. 3.

15 FIG. 5 is an outer partly sectional view, the plugging pistol being shown in the position for which the rear section of the gun is in its open position, the extracting means being also illustrated in their open condition.

FIG. 6 is a transverse sectional view through line VI—VI of FIG. 1, the rear section of the gun being shown in its closed position inside the carcass.

20 FIG. 7 is a cross-sectional view through line VII—VII of FIG. 5, the rear section of the gun being shown in its open position obtained through a pivoting movement.

FIG. 8 is a cross-sectional view through line VIII—VIII of FIG. 5.

25 FIG. 9 is a cross-sectional view through line IX—IX of FIG. 5.

In the embodiment illustrated by way of example and by no means in a limiting sense, the single barreled pistol or apparatus includes a body or carcass 1 provided 30 with a handle 1¹, said body enclosing a cylindrical chamber 1² opening laterally and extending along the longitudinal axis of the gun which includes two sections, a front section 3 and a rear section 6. A longitudinally extending clearance 1³ is formed laterally of the chamber 35 1² in the upper part thereof, while a bearing surface 1⁴ is provided at the end of the chamber 1² for the adjustable fitting and securing of the front section 3 of the gun.

The clearance 1³ in the body or carcass 1 acting as a strap houses the rear boss 4¹ on the arcuate flap 4 pivotally secured to two aligned threaded rods 5 extending longitudinally between terminal lateral projections on the axial section of said carcass 1. Said pivoting flap 4 is in the shape of a cylindrical sector matching the inner outline of the carcass 1, so that its inner surface forms a bearing 45 for the rear section 6 of the cylindrical gun held in position by a screw 7 and by a radial spindle 8 to be described hereinafter.

The rear end of the rear gun section 8 is of a reduced diameter so as to show a bearing surface 16¹ which allows 50 the sliding over it of the extracting ring 9, the periphery of which is welded or otherwise secured to the above-mentioned shouldered spindle 8 (FIG. 7). The latter extends freely through a longitudinal slot 4² formed in the pivoting flap 4 and the shoulder formed on said spindle ensures a fitting and a bearing for a control lever 10 which is held in position on the spindle 8 by the nut 11. The end of the lever 10 engages a slot formed in the boss 4³ on the flap 4, whereby it is longitudinally held by and pivotally secured to a pin 12.

60 It is apparent that with the structure described the control lever 10 is adapted to release the gun section 6 through a pivotal movement of the flap 4 round the spindles 5, as illustrated in FIG. 7, so as to uncover the rear frusto-conical recess 6² in the gun section 6 housing the cartridge carrier T and the corresponding missile 65 13 constituted for instance by a nail. On the other hand and furthermore the control lever 10 allows, through a pivotal movement in the direction of the arrow F of FIG. 5, a rearward sliding of the extracting ring 9 rigid with the spindle 8 and consequently a removal of the cartridge carrier T after the missile has been fired. To this end, it should be remarked that the rear end of the

rear section of the gun shows a squared recess or clearance 6^3 engaged by the corresponding head 9^1 of the extractor ring 9 . Said head 9^1 is provided with a shouldered groove 9^2 housing partly the bead at the rear end of the cartridge carrier 6 , which allows after firing the removing of said cartridge as soon as the extracting ring 9 has receded.

It should also be remarked that the extraction or removal of the cartridge carrier is rendered possible only when the rear gun section 6 is raised into its position of complete release. On the other hand, the longitudinal guiding of the extractor ring 9 with reference to the rear gun section 6 is ensured by a stud 13 secured to the said rear gun section 6 and projecting beyond the latter so as to engage a longitudinal groove 9^3 in the ring 9 .

To the front of the pistol, the carcass 1 carries on its outer bearing surface 1^5 a collar 14 provided with a control lever 14^1 providing for its rotation over a limited angle, whereas said collar 14 carries inwardly a radial projection 15 extending towards the bearing surface 1^5 on the carcass. Said projection 15 passes through one of the openings 1^6 in the carcass 1 which provides for exhaust of the thrust-producing gases, the shaped end 15^1 of said projection reaching the front section 3 of the gun which is screwed over the front portion of the carcass 1 of the pistol. To this end, the front gun section 3 shows a peripheral bearing surface 3^1 in which are cut longitudinal corrugations 3^2 which are adapted to be engaged by the shaped inner end 15^1 of the projection 15 .

It is apparent that the angular shifting of the collar 14 produces directly a rotation of the front section 3 of the gun and ensures thus its axial shifting as a consequence of the screwing or unscrewing of its threaded part 3^3 in the carcass 1 .

Thus, the axial shifting of the front gun section 3 allows either locking without any possible back lash said section in contact with the front end of the cooperating rear section 6 , or else, after an angular movement of the collar 14 in the opposite direction, releasing said rear section 6 which can thenafter rock freely into its released position as disclosed hereinabove.

It should also be mentioned that the plurality of corrugations 3^2 in the front gun section 3 allows a very large number of accurate adjustment combinations adapted to ensure a highly efficient and fluidtight bearing for the end of the front gun section 3 , on the rear section 6 .

Furthermore, the rotary movement of the collar 14 extends over a well-defined sector limited by the angular extent of the openings 1^6 formed laterally in the peripheral bearing surface 1^8 of the carcass 1 .

The splinter-proof shield includes a first member 16 provided with a recessed bearing section 16^1 furthering the assembly of said member 16 over the outer bearing surface 1^5 on the carcass 1 beyond the collar 14 , said member 16 including a protecting cup 16^2 extending over a limited arcuate sector of a circle between free terminal edges. A further member 17 forming part of the shield is constituted by a cup 17^1 extending over an angular sector forming the complement of the angular sector defined by the cup 16^2 , the sum of the angles defined by said sectors being equal to 360° ; the outer diameter 17^2 of the cup 17^1 is equal to the inner diameter of the cup 16^2 . The shield members 16 and 17 are assembled as provided by their fitting or setting on the same ring 18 including an outer collar. Means such as a ball 19 subjected to the thrust of a spring 20 define the relative angular positioning of the cups 16^2 and 17^1 during use, so that they move from one splinter-proof shape to another without any dismantling being required.

The shield system constituted by the members 16 and 17 is held longitudinally on the carcass 1 through the agency of a collapsible abutment rod 21 (FIG. 4) extending through the front end of said carcass, while it is urged rearwardly by a coil spring 21 . Said abutment rod 21 includes a head 21^1 extending beyond the outer bearing 1^5 of the carcass, so as to form an abutment for the

ring 18 rigid with the shield members 16 and 17 . The rod head 21^1 is provided with a flat longitudinal surface 21^2 which allows, upon rotation of the abutment rod 21 , collapsing the head 21^1 onto the bearing surface 1^5 so as to allow dismantling or re-assembling the splinter-proof shield. A ball projecting beyond the end of the carcass 1 cooperates with impressions formed underneath the head 21^1 so as to ensure the accurate positioning of the latter.

The cocking slider 23 is made of two parts and its front part 23^1 rigid with the muzzle 24 of the gun is associated with a compressionally acting return spring 25 centered with reference to the front section 3 of the gun. The adjacent ends of the parts 23 and 23^1 of the slider are adapted to be interconnected by mere cooperating hook-shaped sections 23^2 so as to be rigidly interconnected only for the two longitudinal directions whereas if the front slider part 23^1 is not held in position by the splinter proof shield, said front part disengages automatically the rear part 23 of the slider dropping under its own weight, whereby the cocking of the pistol is prevented.

On the other hand, a safety lever 26 is pivotally carried between the bosses 1^7 of the carcass 1 while a spring 27 urges permanently the front end of said lever 26 into its position for which it abuts against the step 23^3 of the cocking slider which prevents any shifting of the slider which might lead to a cocking of the pistol. The pistol can actually be cocked only after the lever 26 has been released by hand through a pivotal movement thereof and consequently both hands of the operator serve for holding the pistol and pressing on the trigger and for releasing the slider through a pivotal movement of the lever 26 respectively.

It is also possible to associate the rotary movement of the collar 14 with safety means preventing any possible firing whenever the front section 3 of the gun is out of its fluidtight locked position with reference to the rear gun section 6 , which condition is vital. To this end, to the front part 23^1 of the pistol-cocking slider 23 is secured a stud $27'$ which forms a projection engaging a notch 14^2 cut over an arc extending within the thickness of the collar 14 , while a second notch 14^3 in the latter forms a lateral extension for said notch 14^2 but only within a smaller fraction of the collar thickness, so as to form a step 14^4 against which the stud $27'$ is adapted to abut. It should be remarked as a matter of fact that according to the angular setting of the movable collar 14 , the stud $27'$ engages either the deeper notch 14^2 or the shallow notch 14^3 .

When the stud $27'$ on the cocking slider engages the deeper notch 14^2 , said slider is allowed to move transversely, so that a cocking and firing of the pistol are possible. For such a position of the stud $27'$, the collar 14 lies in the angular position for which it locks the front section 3 of the gun in a position for which the firing can be executed under optimum conditions of safety. If in contradistinction the rear section 6 of the gun is not locked through an axial bearing between it and the front section 3 as a consequence of the operator having neglected to make the collar 14 rock, the shallower notch 14^3 provides for an abutment of the stop $27'$ which prevents any translational movement of the cocking slider. Thus, it is impossible to cock and fire the pistol.

The invention also covers means for locking the rear section 6 of the gun in its closed position during the cocking and firing of the pistol.

To this end, a stud 29 provided with a flat lateral surface is rigid with the cocking slider 23 and passes through a longitudinal groove 1^8 formed in the carcass 1 . The inner end of said centering stud 29 engages a recess 6^4 provided with flat lateral sides at the upper end of the gun section 6 and when the slider 23 recedes, said centering stud 29 enters a groove 6^5 of a corresponding cross-sectional shape so as to lock the section 6 and prevents it from moving outwardly through a pivotal movement.

The rear end of the cocking slider 23 is provided with an axial slot 23⁴ across which is pivotally secured at 23⁵ a sear 30 urged constantly in a clockwise direction by a spring 31. A nose 30¹ on the sear 30 cooperates with the shoulder 32¹ on the striker rod 32. A trigger 33 housed within the axial slot 23⁴ is pivotally carried at 33¹ inside the casing 1, so as to cooperate through its nose 33² with a corresponding projection 30² on the sear 30 when the slider 23 is urged rearwardly so as to make said sear rock and constrain the striker to operate.

It should be remarked that within the thickness of the trigger 33 there is inserted a push member 34 projecting beyond the handle of the carcass 1 and pivotally secured to the sear through a spindle 34¹. Said push member 34 engages permanently the lower end of the slider 23 under the action of the thrust exerted by the return spring 35 on the trigger 33. At the end of its return stroke the trigger 33 abuts against the lower surface of the slider 23 through the agency of the transverse stud 36 bearing against the lower surface of the slider 23.

The striker rod 32 slides within a longitudinal opening extending through the body or carcass and is urged forwardly by the thrust exerted by the spring 37 which has been compressed at the moment of the cocking of the pistol so that its pressure is applied against the shoulder 32¹ on the slider rod with the interposition of a ring 38 the shifting of which is limited by a shoulder 1⁹ on the carcass 1, the striker rod 32 continuing its progression under the action of inertia during the firing.

The rear end of the thrust-exerting spring 37 abuts against a plug 39 held inside the carcass 1 by a transverse spindle 40 engaging also a flat longitudinal surface 32² formed on the striker rod 32 thereby to ensure the longitudinal guiding of the latter during its sliding movement.

A weaker spring 41 is fitted in the carcass 1 to the front of the shoulder 32¹ on the striker rod, so as to reliably ensure the rearward movement of the striker rod 32 over a very short distance, after it has struck the cartridge carrier. The conical tip of the striker rod 32 passes through a correspondingly shaped opening formed in the plug 42 fitted in a recess formed in the carcass in registry with the cylindrical chamber 1² of the latter.

The interest of such a single barreled plugging pistol is certain since it ensures through its gun including two associated sections an easy loading and extracting while its use is absolutely safe.

Obviously and as apparent from the preceding disclosure, the invention is by no means limited to the applications thereof and to the embodiments of its different parts described hereinabove and it covers all the modifications thereof falling within the scope of the accompanying claims.

What I claim is:

1. A plugging pistol adapted to fire a cartridge carried by a cartridge carrier comprising a casing defining a cylindrical chamber with an open front end, an arcuate lateral opening adjacent said chamber along the rear thereof and a coaxial channel opening into the rear end of the chamber and in turn open at the rear end thereof, a gun structure carried in said chamber and including a front section threadedly engaged with the casing at the front open end of said chamber, and a rear section independent of the front section, a collar rotatably encircling said casing and coupled with the front gun section to rotate and axially shift the latter between a rear operative position in abutting engagement with the rear section and a front inoperative position spaced from the rear section, a flap rigid with the rear section and pivotally secured to the casing for movement about an axis parallel with the axis of the cylindrical chamber between an operative position in which the flap closes the lateral opening in the chamber and positions the rear gun section in registry with the front section and an inoperative position in which the flap uncovers said lateral opening and shifts the rear gun section outside the body into a cartridge carrier load-

ing and extracting position, a striker in said channel, a cocking slider adapted to slide longitudinally in said casing to an operative position to cock the striker, trigger means for releasing the cocked striker, said slider including a stud engaging the rear gun section upon setting of the cocking slider in its operative position to hold said rear gun section in its operative position, an extracting ring surrounding the rear section of the gun structure and adapted to slide longitudinally of the latter and a lever rigid with said ring and pivotally carried by the flap both to control the position of the latter and to shift said ring between a front inoperative position and a rear operative position, said ring in the rear operative position causing extraction of the cartridge carrier out of the rear gun section.

5 10 15 20 25 30 35 40 45 50 55 60 65 70

2. In a plugging pistol as claimed in claim 1, the provision of a cup-shaped splinter shield extending coaxially at the front of the casing and including two arcuate parts extending over angles the sum of which is equal to 360° and means controlling the relative angular position of said parts.

3. In a plugging pistol as claimed in claim 1, wherein said extracting ring has a longitudinal slot, a stud on the rear section of the gun structure engaging said slot in the ring to allow the latter to slide longitudinally of said rear section, an arcuate collar rigid with the inside of the ring and engaging the rear end of the rear gun section, said collar having an underside which engages the rear end of the cartridge carrier such that with the ring in the rear operative position the ring collar provides for the extraction of the cartridge carrier out of the rear gun section.

4. A plugging pistol as claimed in claim 1, wherein the front gun section is longitudinally corrugated and the casing is provided with arcuate slots for the exhaust of the burnt gases produced by the cartridge, said pistol comprising furthermore an outer control handle rigid with the collar and an inner projection rigid with the collar and engaging through one of said slots a corrugation at the periphery of the front gun section.

5. A plugging pistol as claimed in claim 1, comprising a muzzle for the gun structure, a spring coaxial with the gun structure and carrying said muzzle coaxially with the gun structure, a front extension of the cocking slider rigid with the muzzle and engaging releasably said cocking slider and a stud rigid with the outer surface of said extension the collar being provided inwardly with a notch adapted to be engaged by the stud on the extension of the cocking slider when the collar is in its operative angular position so as to release the stud and allow a longitudinal shifting of the cocking slider into its operative position, said stud on the extension engaging the inner surface of the collar when the collar is out of its operative position to prevent said longitudinal shifting.

6. In a plugging pistol as claimed in claim 1, the provision of a cup-shaped splinter shield extending coaxially at the front of the casing and including two arcuate parts extending over angles the sum of which is equal to 360° and means controlling the relative angular position of said parts, a muzzle for the gun structure, a spring coaxial with the gun structure and carrying said muzzle coaxially with the gun structure, a front extension of the cocking slider rigid with the muzzle engaging releasably said cocking slider and held by the inner periphery of the shield in operative relationship with the cocking slider.

7. In a plugging pistol as claimed in claim 1, the provision of a safety lever pivotally secured to the outer surface of the casing adapted to engage the cocking slider to prevent operation thereof and a spring urging said lever into its slider-engaging position.

8. A plugging pistol as claimed in claim 1, comprising a shoulder rigid with the striker, a rearwardly facing step in the channel, a plug closing the opening at the rear end of the channel, a ring surrounding the striker to the rear of its shoulder and adapted to abut against said step, a

spring inserted between the plug and the ring to urge the striker forwardly towards the cartridge carrier through the agency of said ring upon operation of the trigger means and a weaker spring engaging the front surface of the collar on the striker to urge the latter rearwardly after its forward thrust.

9. A plugging pistol as claimed in claim 1, wherein the trigger system includes a sear engaging the striker, a trigger pivotally secured to the body and adapted when the cocking slider is in its operative position to release the sear and an independent pusher member pivotally secured to the trigger and controlling the latter and a spring urging the trigger away from the sear and the pusher member against the outer surface of the slider adjacent its rear end.

10. In a plugging pistol as claimed in claim 1, the provision of a cup-shaped splinter shield extending coaxially at the front of the casing and including two arcu-

ate parts extending over angles the sum of which is equal to 360° , means controlling the relative angular position of said parts, a rod revolvably carried by the front end of the casing and including a head part of which is cut off, a ring secured to both parts of the shield and held fast between the head and the rod and the casing for a predetermined angular position of the rod for which the cut off part of the head lies outside the ring and a spring urging said head towards the casing.
